UNITED STATES PATENT OFFICE

2,583,059

MATRIX BAND RETAINER FOR ANTERIOR TEETH AND TRACTION INSTRUMENTS THEREFOR

Benjamin F. Tofflemire, Lafayette, Calif.

Application March 24, 1950, Serial No. 151,604

7 Claims. (Cl. 32—63)

1

The present invention relates to improvements in a matrix band retainer for anterior teeth and traction instrument therefor. It embodies improvements over the dental matrix band retainers shown in my United States Letters Patent Numbers 2,437,703, issued April 13, 1948, and 2,502,903, dated April 4, 1950.

Moreover, this invention has particular reference to improvements with respect to the retainer forming part of the disclosure in my copending application on "Anatomical Contact-Forming Dental Matrix Bands For Anterior Teeth," Serial No. 135,047, filed in the United States Patent Office on December 27, 1949.

Broadly speaking, each of the earlier cases provides a frame having a matrix band-supporting head at one end thereof. This band is slotted to slidably receive an intermediate portion of a looped matrix band. The band itself extends from the head so as to encircle a patient's tooth. In each case the frame has a block slidably mounted thereon, which is arranged to have the ends of the matrix band clamped thereto. Retraction of the block away from the head draws the band into snug engagement with the axial contour of the banded tooth, while advancement of the block toward the head releases the band for removal from the tooth.

The matrix retainers disclosed in the foregoing mentioned patents and pending application further include a threaded spindle and a rotatable sleeve for retracting or advancing the slidable block. These parts constitute portions of the assembled retainer, and project from the patient's mouth for operation.

With this background in mind, the present invention provides a matrix band retainer, and a separate detachable traction instrument for actuating a matrix band-clamping block on the retainer. In this manner, the retainer can be utilized for applying the band around a patient's tooth; the traction instrument employed for drawing the band into engagement with the tooth; and thereafter this instrument may be detached, and laid aside until subsequently required. The detachment of the traction instrument will afford unobstructed view of the operative field.

A further object of this invention is to provide a retainer and instrument of the character described, which is simple and compact in construction, and actuated quickly with the minimum amount of effort on the part of the operator. Furthermore, I provide a matrix band having special stops at its ends for engagement with the slidable block.

2

Other objects and advantages will appear as the specification continues. The novel features will be set forth in the claims hereunto annexed.

5 For a better understanding of my invention, reference should be had to the accompanying drawings, forming part of this application, in which:

Figure 1 is a plan view of my matrix band retainer and its traction instrument, the latter being shown in open position;

Figure 2 is a vertical transverse sectional view taken along the line II—II of Figure 1;

Figure 3 is a side elevational view of Figure 1;

15 Figure 4 is a view similar to Figure 1, but disclosing the traction instrument closed, with the retainer holding the matrix band tightly around a banded anterior tooth;

Figure 5 is a side elevational view of the matrix 20 retainer clamping the band around the tooth, the traction instrument having been detached;

Figure 6 is a mesial-distal view of the banded tooth, looking at the labial surface (lip side) thereof, as suggested by the lines VI—VI of 25 Figure 4, the band being shown in section;

Figure 7 is an isometric view of the retainer frame; and

Figure 8 is an isometric view of the two parts 30 of the slidable block that I employ.

While I have shown only the preferred form 35 of my invention, it should be understood that various changes, or modifications, may be made within the scope of the appended claims without departing from the spirit thereof.

Detailed description

In carrying my invention into practice, I make use of a dental matrix band indicated generally 40 at A, which has been illustrated as being applied around an anterior tooth B. This band is identical with the one disclosed in my copending application, Serial No. 135,047, filed in the United States Patent Office on December 27, 1949, excepting for the addition of stops or enlargements 45 10 that are fixed to the ends of the band (see Figures 1, 3 and 5).

This matrix band utilizes the principle of complete coronal surface-area adaptation of the anterior tooth. Concavo-convex eminences 11 are fashioned on this band, which define concavities on the tooth-embracing face of the band disposed to register with the normal points of contact of the tooth being restored (see Figure 6).

55 These indentations are positioned on both the mesial and distal aspects of the banded tooth, and

receive extended portions of interproximal fillings 12. These portions of the filling will reform eminences projecting toward the adjacent teeth C at the normal points of contact between these teeth. A similar filling 14 may be packed on the labial surface (toward lips) at the same time, and this filling covered by a crescent-shaped member 15 (see Figure 6).

In its structural features, the band is provided with a central cingulum-receiving notch 16 adapted to fit over the cingulum 17 of the tooth and laterally-disposed gingival (gum)-facing notches 18 shaped to follow the gingival curvature of the tooth in the interproximal areas (between the teeth).

It will be noted further that the incisal-facing edge of the matrix band has two smaller incisal notches 19. These notches encircle the mesial and distal incisal angles, respectively, in such a manner that perfect adaptation to the tooth is secured without wrinkles, pleats, puckering, or undesirable irregularities. The band is fashioned with a preshaped offset 20 to fit against the lingual fossa area and the natural grooves adjacent thereto on the lingual (tongue side) inclined plane 21 of the tooth.

After the loop A' is applied around the axial contour of the tooth, the end sections 22 of the matrix band are brought together in parallel relation with one another and project from the patient's mouth. The stops or enlargements 10 are fixed to opposite sides of these parallel arms at the free ends thereof, as shown in Figure 1.

Referring to Figures 1 to 5, inclusive, my improved matrix band retainer is designated at D. This retainer includes a head or shoe 23 at its forward end, which is slotted at 24 (see Figure 7) to define a pair of spaced-apart fingers 25. The head has a concaved face 26 shaped to conform with the labial surface 27 of the banded tooth.

Moreover, a pair of rearwardly-extending parallel bars 28 are fixed to the head 23, and are adapted to project outwardly from the patient's mouth when the concaved face 26 is moved toward the labial surface of the tooth. A clamping block D' is slidably mounted on the bars 28 for adjustment along the length thereof.

This clamping block includes upper and lower parts 29 and 30, respectively, which are arranged in confronting relation with one another above and below the bars 28, respectively. Horizontal grooves 31 are provided in the confronting faces of these block parts to slidably receive the bars 28 (see Figures 2 and 8). A stem 32 is fixed to the lower part 30 and rises through an opening 33 fashioned in the upper part 29.

For the purpose of drawing the upper and lower parts of the clamping block D' together in clamping relation with the interposed bars 28, I make use of a lever 34. This lever is swingably secured to the upper portion of the stem 32 by a pin 35, and has a cam 36 thereon (see Figure 5). This cam is designed to allow a slight separation of the parts 29 and 30 when the lever is raised into upright position, as shown by dot-dash lines in Figures 2, 3 and 5. However, upon swinging this lever into horizontal position, as disclosed by full lines in Figure 5, the parts 29 and 30 are clamped upon the interposed bars 28.

In order to facilitate manual grasping of the upper and lower parts 29 and 30, respectively, and sliding them along the bars 28 when the lever cam 34-36 is released, I have provided concaved faces 37 along opposing sides of these two parts (see Figure 8). Thus these faces may be grasped 75 by the operator. The handle 15a is positioned

readily by an operator for adjusting them lengthwise along the bars 28.

As illustrated in Figures 2 and 8, a vertical slot 38 extends upwardly from the underneath exposed face of the lower part 30. This slot continues upwardly into the stem 32, and registers with a companion slot 39 formed in the underside of the upper part 29.

The slots 24 and 38-39 in the head 23 and clamping block D', respectively, open toward a common plane and are arranged along the longitudinal axis of my matrix band retainer. These slots are dimensioned for edgewise insertion of the end sections 22 of the matrix band thereto. When the band is thus introduced into the retainer, the stops or enlargement 10 at the ends of the band are engaged in back of the clamping block D', as clearly shown in Figures 1, 3 and 5.

Thus when the lever cam 34-36 is raised and the block D' is retracted away from the head 23, the matrix band A will be drawn tightly around the tooth B. At this time, the band will be disposed between the concaved face 26 of the head and the labial surface 27 of the tooth, as in Figure 5. The lever cam will lock the clamping block in any position to which it is adjusted by merely swinging the lever 34 into horizontal position. In order to release the band, the lever 34 is raised, the block D' moved toward the head 23, and thereafter the retainer may be disengaged very easily from the matrix band.

My traction instrument is indicated generally at E. It includes a body member 40 having a reciprocable plunger 41 mounted therein. Scissor-like handles 42 are hingedly secured by pins 43 to this body member. The outer end of a pair of links 44 are hinged by pins 45 to the handles, while the inner ends of these links are attached by a pin 46 to the rear part of the plunger 41. The arrangement is such that separation of the handles, as in Figure 1, will retract the plunger, while movement of the handles toward one another, as in Figure 4, will project the plunger forwardly with respect to the body member 40 of the traction instrument.

In Figures 1 and 3, I have shown a pair of spaced goose-neck-shaped arms 47 projecting forwardly from the body member 40 so as to overlie the clamping block D. These arms terminate in hooks 48 at their forward ends, which are adapted to engage over the forward face of the clamping block, as shown in Figure 3. The arms 47 are spaced above the body member 40, and are positioned on opposite sides of the stem 32 and the lever cam 34-36 when the traction instrument is applied to the matrix retainer. Thus the lever 34 may be raised after the traction instrument has been applied to the retainer to permit the block D' to be pulled rearwardly; also, the lever can be lowered to clamp the block D' to the bars 28 before the instrument is detached.

The plunger 41 has a transversely-extending pin 49 at its forward end, which is adapted to be inserted into notches 50 formed in the back ends 65 of the bars 28 (see Figure 7). Thus when the hooks 48 are positioned over the front of the block D', the pin 49 engaged in the notches 50, the block will be retracted relative to the bars 28 upon swinging the handles 42 toward one another.

In Figure 6, I show the crescent-shaped member 15 having a handle 15a rising therefrom. The upper end 15b of this handle curves away from the banded tooth so that it may be easily grasped by the operator. The handle 15a is positioned

between the matrix band and the banded tooth. The tooth-embracing face of the member 15 is spoon-shaped so as to fit against and conform with the labial surface of the tooth.

Summary

The matrix band A is placed around the axial contour of the selected anterior tooth B, with the central notch 16 fitting over the cingulum 17, and the end sections 22 of the band passing outward labially past the mesial and distal contact points of the tooth (see Figure 3).

Then gingival wedges 51 are placed firmly along the outer surfaces of the band at the free margin of the gingival tissues, as shown in Figure 6. This will hold the band securely adapted to the margins of the prepared cavities, preventing extrusion of the filling material during compression and curing. Acrylic materials may be used for the fillings, but I do not wish to be limited in this respect.

The free sections 22 of the band may be opened up laterally, that is, spread mesially and distally, after the wedges are placed. This will give access to the cavities on the mesial, distal and labial aspects, permitting the fillings 12 and 14 to be packed. Next, the crescent-shaped member 15 is applied over the labial filling.

Thereafter, the free sections 22 of the matrix band are brought together, as in Figure 1, and inserted edgewise into the slots 24 and 38-39 of the head 23 and clamping block D', respectively. Care is taken to place the stops or enlargements 10 on the ends of the matrix band in a position rearwardly of the clamping block. Now the lever 34 is partially depressed so as to create some friction between the block and the bars 28 of the retainer.

As the next step, the operator introduces the transverse pin 49 on the plunger 41 into the notches 50 at the back ends of the bars 28. Now the traction instrument E is rocked from the dot-dash line position shown in Figure 3 into the full line illustration therein, engaging the hooks 48 over the front face of the clamping block D'.

At this time the handles 42 are spread apart in the manner shown in Figure 1. Then the operator moves the handles toward one another, as in Figure 4. This will result in pushing the plunger 41 and the bars 28 forwardly, and retracting the block D' away from the head 23, tightening the band A around the tooth B. Thereupon the lever 34 is swung into horizontal position to clamp the block D' upon the bars 28. The traction instrument, while engaged with the retainer, may be held in one hand of the operator to steady the retainer during clamping of the block D' to the retainer bars 28.

The operator now detaches the traction instrument E from the matrix band retainer D. During this detachment, the arms 47 are moved upwardly; and the lever 34 will not interfere with such movement, since the arms are spaced laterally beyond the lever. The traction instrument is laid to one side until needed subsequently.

In removing the retainer, the lever 34 is raised into vertical position, thus releasing the clamping action of the block D' from the bars 28. The operator grasps the concaved faces 37 of the parts 29 and 30 of the block and advances the latter toward the head 23 of the retainer. Then the retainer may be lifted from the matrix band.

The curved head 23 of the retainer not only guides the band in following the contour of the

tooth, but securely holds the band in position with a spring tension throughout the curing process or setting of the fillings. The resilient spring tension exerted by the specially-formed band and retainer has been found most useful in the prosthetic moulding of acrylics during processing.

It will be noted that I have illustrated the matrix band, retainer and traction instrument as being used in connection with a lower anterior tooth. Of course, these parts will be inverted when operating on upper anterior teeth.

I claim:

1. In combination, a matrix band retainer and a detachable traction instrument therefor; the retainer including: a slotted head for slidably receiving an intermediate portion of a looped matrix band, with the loop extending from the head; at least one bar fixed to the head to project rearwardly therefrom; a block adjustably mounted on the bar for movement therealong, and having end sections of the matrix band removably anchored to the block; and means for clamping the block in adjusted position on the bar; the traction instrument including: a body member having a reciprocable plunger mounted therein for forward and rearward movement; the plunger being detachably connected to the bar of the retainer; at least one arm rigid with and projecting forwardly from the body member and having a hook removably engaging over a forward face of the block for pulling the block rearwardly along the bar to constrict the matrix band loop when the plunger is projected forwardly; and means for reciprocating the plunger.
2. In combination, a matrix band retainer and a detachable traction instrument therefor; the retainer including: a slotted head for slidably receiving an intermediate portion of a looped matrix band, with the loop extending from the head; at least one bar fixed to the head to project rearwardly therefrom; a block adjustably mounted on the bar for movement therealong, and having end sections of the matrix band removably anchored to the block; and means for clamping the block in adjusted position on the bar; the traction instrument including: a body member having a centrally-disposed reciprocable plunger mounted therein for forward and rearward movement; the plunger being detachably connected to the bar of the retainer; a pair of spaced-apart arms rigid with and projecting forwardly from the body member and arranged on opposite sides of the plunger; the arms having hooks removably engaging over a forward face of the block for pulling the block rearwardly along the bar to constrict the matrix band loop when the plunger is projected forwardly; and means for reciprocating the plunger.
3. The combination as set forth in claim 2, in which the blocking-clamping means includes a lever-operated cam disposed between the arms of the traction instrument, with the lever being swingable in a vertical plane without interference by said arms.
4. In a matrix band retainer; a head having a slot extending thereinto from an exposed surface of the head to slidably receive an intermediate portion of a looped matrix band, with the loop projecting from the head; at least one bar fixed to the head to project rearwardly therefrom; a block adjustably mounted on the bar for movement therealong, and having a slot extending thereinto from an exposed surface of the block for edgewise insertion of end sections of the

matrix band thereinto; this block having front and rear faces; the block slot extending between these front and rear faces of the block; the rear face of the block being adapted to have stops on the ends of the matrix band abut thereagainst; the block including upper and lower parts disposed above and below the bar, respectively; and means including a lever-operated cam for drawing these parts toward one another to clamp them upon the interposed bar.

5. In a matrix band retainer: a head having a slot extending thereinto from an exposed surface of the head to slidably receive an intermediate portion of a looped matrix band, with the loop projecting from the head; at least one bar fixed to the head to project rearwardly therefrom; a block adjustably mounted on the bar for movement therealong, and having a slot extending thereinto from an exposed surface of the block for edgewise insertion of end sections of the matrix band thereinto; the block further having a rear face against which stops on the ends of the matrix band are abuttable; the block including upper and lower parts disposed above and below the bar, respectively; a stem secured to one of the block parts and projecting through an opening in the other part; a swingably-mounted cam connected to the stem and bearable against said other part of the block; the cam drawing the parts toward one another to clamp them upon the interposed bar when the cam is swung in one direction; and means for swinging the cam.

6. In a matrix band retainer: a head having a slot extending thereinto from an exposed surface of the head to slidably receive an intermediate portion of a looped matrix band, with the loop projecting from the head; at least one bar fixed to the head to project rearwardly therefrom; a matrix band anchoring block adjustably mounted on the bar for movement therealong, and having a slot extending thereinto from an exposed surface of the block for edgewise insertion of end sections of the matrix band thereinto; the block including upper and lower parts disposed above and below the bar, respectively; a stem secured to one of the block parts and projecting through an opening in the other part;

a swingably-mounted cam connected to the stem and bearable against said other part of the block; the cam drawing the parts toward one another to clamp them upon the interposed bar when the cam is swung in one direction; and means for swinging the cam.

7. In a traction instrument for moving a sliding matrix band anchoring block along bars of a dental matrix band retainer: a body member having a centrally-disposed reciprocable plunger mounted therein for forward and rearward movement; a horizontally-disposed transverse pin at the forward end of the plunger projecting beyond opposite sides of the plunger, and positioned for engagement with rear portions of the retainer bars; a pair of spaced-apart goose-neck-shaped arms rigidly fixed to and projecting forwardly from the body member; these arms having offset portions adapted for fitting over the sliding block of the retainer, and further being provided with spaced-apart parallel hooks disposed for engaging over a forward face of this block; the transverse pin being arranged rearwardly of the hooks; the arms being disposed on opposite sides of the axis of reciprocation of the plunger; and means including scissor-like handles for reciprocating the plunger; these handles being swingable in a common plane; the hooks projecting in the same direction from the arms and being arranged substantially at right angles to the plane of movement of the handles.
